UNITED STATES PATENT OFFICE.

CHARLES A. BAILEY, OF CROMWELL, CONNECTICUT, ASSIGNOR TO THE
J. & E. STEVENS COMPANY, OF SAME PLACE.

DESIGN FOR A MONEY-BOX.

SPECIFICATION forming part of Design No. 31,275, dated July 25, 1899.

Application filed June 22, 1899. Serial No. 721,488. Term of patent 7 years.

To all whom it may concern:

Be it known that I, CHARLES A. BAILEY, a citizen of the United States, residing at Cromwell, in the county of Middlesex and State of Connecticut, have invented and produced a new and original Design for Money-Boxes, of which the following is a specification, reference being had to the accompanying drawings, forming a part thereof, and in which—

10 Figure 1 is a front elevation of a money-box, showing my new design. Fig. 2 is a side view.

The object of my invention is to provide a money-box or toy bank of a design that shall be ornamental in appearance, being patterned 15 to imitate a miniature bank-building embodying certain peculiar features.

To this end the essential or material feature of the design consists of the front presenting the ornamental base A, having centrally the 20 steps a; half-round columns or door-posts B, extending upward from the base and terminating in ornamental caps b; a door-lintel D and shell-scrolls E at each side thereof; round window-like projections F above the lintel; 25 an ornamental band G, extending across the upper part of the front, and a gable-roof with round projections representing chimneys.

The horizontal coin-slot h is directly above the ornamental band G, and the front is further ornamented by the gable-window I and 30 plain windows and door K and K', respectively.

The front is provided with horizontal lines connected by short vertical lines at equal distances apart and breaking joint to imitate a 35 brick structure, while the sides of the box are provided with horizontal lines and openings, as shown.

The back of the money-box is similar in all respects to the front, with the exception that 40 the coin-slot is omitted in order that the said box may be made in duplicate sections.

Having thus described my invention, what I claim as new, and desire to secure by Letters Patent, is—

45 The design for a money-box, as herein shown and described.

In testimony whereof I affix my signature in the presence of two witnesses.

CHAS. A. BAILEY.
